[57] CLAIM

The ornamental design for a drawer panel, as shown and described.

DESCRIPTION

FIG. 1 is a front, right side perspective view of a drawer

panel showing my design, and the front, left side perspective view is a mirror image;

FIG. 2 is a front view of the drawer panel of FIG. 1;

FIG. 3 is a front, right side perspective view of a second embodiment of a drawer panel showing my design, and a front, left side perspective view is a mirror image;

FIG. 4 is a front view of the drawer panel of FIG. 3;

FIG. 5 is a front, right side perspective view of a third embodiment of a drawer panel showing my design and the front, left side perspective view is a mirror image;

FIG. 6 is a front view of the drawer panel of FIG. 5;

FIG. 7 is a cross sectional view at 7—7 in FIG. 2 and is representative of similar cross sections of the drawer panels in FIGS. 4 and 6;

FIG. 8 is a front, right side perspective view of a fourth embodiment of a drawer panel showing my design and the front, left side perspective view is a mirror image;

FIG. 9 is a front view of the drawer panel of FIG. 8;

FIG. 10 is a front, right side perspective view of a fifth embodiment of a drawer panel showing my design and the front, left side perspective view is a mirror image;

FIG. 11 is a front view of the drawer panel of FIG. 10;

FIG. 12 is a cross section at 12—12 in FIG. 9 and is also representative of a similar cross section of the drawer panel in FIG. 11;

FIG. 13 is a front, right side perspective view of a sixth embodiment of a drawer panel showing my design and the front, left side perspective view is a mirror image;

FIG. 14 is a front view of the drawer panel of FIG. 13;

FIG. 15 is a front, right side perspective view of a seventh embodiment of a drawer panel showing my design and the front, left side perspective is a mirror image;

FIG. 16 is a front view of the drawer panel of FIG. 15; and,

FIG. 17 is a cross sectional view at 17—17 in FIG. 14 and is representative of a similar cross section of the drawer panel in FIG. 16.

The features shown in broken lines do not form part of the claimed design.
